APPARATUS FOR RENOVATING JOURNAL
BOX PACKINGEdwin S. Pearce, Indianapolis, Ind., assignor to
Railway Service & Supply Corporation, In-
dianapolis, Ind., a Corporation of IndianaApplication September 18, 1930
Serial No. 431,660

4 Claims. (Cl. 210—66)

The invention disclosed in this application relates to apparatus for renovating the fibrous waste part of journal box packing.

In the renovation of used or dirty journal box packing it is essential that the waste and the oil parts be separated so that both parts may be properly renovated thereafter, and the renovation or reclamation of the former part, to wit, the waste part, is the one with which this application is concerned. The inbound dirty packing contains many undesirables such as fine lint, in suspension in the oil and mingled with the waste fibers, dirt of all kinds, short ends of fibers, metal fragments, and many other varied types of impurities. As will be readily understood, all of these impurities must or at least should be removed. Some of them pass out with the oil part when it is separated from the waste part but others thereof remain with the waste part, furnishing 20 contamination therefor aside from giving it a dirty, unsightly color or appearance.

The object of the present invention therefore is to provide apparatus for performing the steps of separating the oil and waste parts and of thoroughly cleansing the latter, ready for the removal therefrom, if necessary, of such undesirables as heavy pieces of dirt, grit or metal. The invention contemplates also the oil washing or scrubbing of the waste fibers to restore their former color and to render them as good as, indeed better than, new waste in that most of the short ends and fine lint are removed.

Briefly stated, the apparatus consists of an extractor type of device including a vertically disposed rotatable basket for receiving the packing and having an undulating, corrugated or fluted wall presenting vertical ridges and valleys adapted to support the packing in an unmatted, porous condition to permit the free circulation through 40 and discharge from the packing not only of the oil originally contained therein but also, additional hot oil furnished for the purpose of washing out and removing substantially all traces of the old oil, and substantially all of the undesirables, such as lint, dirt and the like, leaving the waste part with substantially fiber saturation only and ready for impregnation with new or renovated oil.

The invention is set forth in the following description, drawings and claims.

Referring to the drawings, Fig. 1 is a top plan view of a portion of a packing reclamation plant; embodying the apparatus forming the subject matter of the present application; Fig. 2 is a front elevation thereof; Fig. 3 is a view partly in top

plan and partly in section showing the extractor basket; Fig. 4 is a view of the basket partly in side elevation and partly in section; Fig. 5 is a vertical section through the distributing device arranged at the center of the basket; Fig. 6 is a cross section upon the line 6—6 of Fig. 5; and Fig. 7 is a cross section upon the line 7—7 of Fig. 5.

In the embodiment shown, 1 represents a drainage tank connected by a discharge pipe 2, either 65 with an underground sump generally indicated at 3 or with an oil renovating plant, not shown. This tank has an upper grid 4 upon which the inbound dirty packing is placed and any free oil present in the packing drips into this tank. EX- 70 tending from both ends of this tank are drain boards 5 draining back to the tank and extending to extractor type, oil treating devices.

There are two of these extractor devices and since they are of identical construction a description of one will suffice for both. Each comprises a lower support 6 and a curb 7 connected at the bottom to suitable drainage pipes 8 leading to a main drain 9 in turn leading to the dirty oil sump 3. Any oil deposited in the curb 7 will therefore find its way to the dirty oil sump. Each of the extractors has suitable bearings, not shown, for supporting an extractor shaft 10, Figs. 3 and 4, and upon this shaft is mounted a basket bottom 11 carrying at the center a distributor base 85 12 supporting a central cylindrical distributor 13 partially closed at the top by a flange 14 and provided in its side wall with vertically disposed, circumferentially arranged slots 15. These slots, which are arranged in staggered relation, as 90 shown, increase in width from the bottom toward the top of said wall, that is, the higher the slots the wider they are, whereby oil supplied to this distributor will be distributed evenly in a radial direction within the extractor basket and 95 throughout the height of the packing therein.

Secured to the periphery of the extractor basket bottom 11 is a perforated basket side wall 16 connecting at its top to the usual extractor basket top flange 17. Within this wall 100 and supported by it is the means for preventing undue matting or compressing of the fibrous waste part, said means being shown in the present embodiment as in the form of a fluted wire mesh lining 18. The flutes are spread, as shown, 105 to provide a multiple pointed star arrangement in cross section, the object being to present to the packing an undulating wall in the form of vertical ridges and valleys which will support the material, prevent its packing and matting, and 110

provide the maximum of discharge area for any oil or any undesirable material in the fibrous waste part. As is usual, each extractor is provided with a suitable cover, indicated at 19, Fig. 1, 5 and having a central opening 20 therein for the reception of an oil supply pipe 21 connected to an oil supply line 22. This pipe projects down through the opening 20 and into the central opening of the flange 14 of the distributor. In 10 order to heat the oil to the proper extent for oil removal and waste washing purposes, the line 22 may lead from an indirect heater 23 provided with a primary steam circulating heating coil 24 arranged therein.

15 In use the inbound dirty packing is loaded into the basket of the extractor from the drainage grid 4 and drain board 5 and the basket is rotated at a moderate speed, say 800 to 900 R. P. M. This speed is insufficient to pack or mat the packing 20 at the periphery of the basket in view of the undulating lining 18. If the oil of the packing is sufficiently fluid to pass out as a result of rotation at this speed it may do so, and some usually does but ultimately hot dirty oil or hot clean oil 25 is supplied to the distributing member in the manner theretofore disclosed and is caused to forcibly and uniformly pass through the interstices of the packing, mingle with the oil therein, and pass out with it into the curb. As this oil 30 washing operation is continued, the fibers of the waste part of the packing are thoroughly scrubbed and any moisture present in the waste part and indeed in the oil part is vaporized and passes off. After treatment in this way for a 35 sufficient length of time, the fibrous waste part is left clean and entirely rid of water moisture. In order to reduce the oil content of the waste part, the supply of oil is cut off and the basket driven at a higher speed, if desirable, to thereby 40 reduce the oil content of the waste part to fiber saturation only and to remove all free oil deposits in the interstices of the waste part. If desired, clean oil supplied to pipes 25 from any suitable 45 source of clean oil supply may be passed through the waste part to change the films of oil forming the fiber saturation to clean removed oil film. It is quite obvious from the foregoing that the 50 entire lint content of the waste is carried away with the oil leaving the waste part entirely lint and dirt free, it only being necessary in some cases to afterwards tumble the waste, as is the usual practice other undesirables present, if any, such as large bits of metal, etc.

55 What I claim is:

1. In a rotatable container for receiving for treatment fibrous journal box waste, an oil distributing device vertically arranged in said container on substantially the central axis thereof, said device comprising a tubular structure having its lower end closed and secured to the bottom wall of said container and having its upper end provided with an opening to receive oil, for distribution or delivery into the waste in said container, the side wall of said tubular structure 60 being provided, from the bottom wall of said container to substantially the top of the side wall thereof, with vertically disposed oil distributing

slots said slots being of increasing width from the bottom ones thereof to the top ones thereof, whereby an even distribution of oil by said slots is effected.

2. In a rotatable container for receiving for treatment fibrous journal box waste, an oil distributing device vertically arranged in said container on substantially the central axis thereof, said device comprising a tubular structure having its lower end closed and secured to the bottom wall of said container and having its upper end provided with an inwardly extending annular flange and a central opening to receive oil for distribution or delivery into the waste in said container, the side wall of said tubular structure being provided, from the bottom wall of said container to substantially the top of the side wall thereof, with vertically disposed oil distributing slots, said slots being of increasing width from the bottom ones thereof to the top ones thereof, whereby an even distribution of oil by said slots is effected.

3. In a rotatable container for receiving for treatment fibrous journal box waste, an oil distributing device vertically arranged in said container on substantially the central axis thereof, said device comprising a tubular structure having its lower end closed and secured to the bottom wall of said container and having its upper end provided with an opening to receive oil for distribution or delivery into the waste in said container, the side wall of said tubular structure having substantially its entire area provided with circumferentially arranged, vertically disposed oil distributing slots in staggered formation, said slots being of equal length and of increasing width from the bottom ones thereof to the top ones thereof, whereby an even distribution of oil by said slots is effected.

4. In a centrifugal extractor for treating journal box packing made up of a fibrous waste part and an oil part, a rotatable basket for receiving said packing and having a bottom wall structure and a perforated side wall structure, said side wall structure having disposed around its circumference a series of vertically disposed, inwardly extending substantially rigid ridges of wedge or triangular shape, said ridges being side by side and being perforated throughout substantially their entire areas, and an oil distributing device 115 vertically arranged in said basket on substantially the central axis thereof, said device comprising a tubular structure having its lower end closed and secured to the bottom wall of said basket and having its upper end provided with an opening 120 to receive oil for distribution or delivery into the packing in said basket, the side wall of said tubular structure being provided, from the bottom wall structure of said basket to substantially the top of the said wall structure thereof, with circumferentially arranged, vertically disposed oil 125 distributing slots arranged in staggered formation, said slots being of increasing width from the bottom ones thereof to the top ones thereof, whereby an even distribution of oil by said slots 130 is effected.

EDWIN S. PEARCE.
